UNITED STATES PATENT OFFICE.

GEORGE WARREN WILLIAMSON, OF INDIANAPOLIS, INDIANA.

JACK.

Application filed March 30, 1922. Serial No. 547,979.

To all whom it may concern:

Be it known that I, GEORGE WARREN WILLIAMSON, a citizen of the United States, residing at Indianapolis, in the county of Marion and State of Indiana, have invented 5 a new and useful Jack, of which the following is a specification.

The object of my invention is to produce an efficient lifting jack, the load-engaging 10 member of which may be either raised or lowered by proper manipulation of the operating lever without preliminary adjustment of any other member.

The accompanying drawings illustrate 15 my invention: Fig. 1 is an elevation of one side of a jack embodying my invention; Fig. 2, an elevation of the other side; Fig. 3, a fragmentary section of the base showing an adjacent portion of the main stem; 20 Fig. 4, an elevation of the removable section of the operating lever; Fig. 5, a perspective of one of the clutch members; Fig. 6, a section on line 6—6 of Fig. 9, of the load-carrying unit; Fig. 7, a section on line 25 7—7 of Fig. 6 with the parts in position for lifting action; Fig. 8, a section, on the plane of Fig. 7, with the parts in position for lowering action; Fig. 9, a section on line 9—9 of Fig. 6; Fig. 10, a section on line 30 10—10 of Fig. 7; and Fig. 11, a section on the plane of Fig. 10 with the parts shifted as in a lowering action.

In the drawings, 20 indicates a main stem, 35 preferably of channel cross section, provided at its upper end with a head 21 having a lateral projection to which is pivoted a depending finger 22 so as to form a hook having a recess 23 so that the structure may be hung upon a support.

40 Finger 22 is separably pivoted on head 21 by a bolt 24 and swing in one direction is limited by a stud 25 cooperating with a stop-shoulder 26. Finger 22 is provided with a gripping cam 27 cooperating with a gripping surface 28 so that a wire or similar object may be gripped.

45 Stem 20 is supported by a base 29, either in the position shown in Figs. 1 and 2, or in Fig. 3 and is retained by the movable bolt 30. Base 29 is provided with a primary socket 31, in which stem 20 may be supported vertically, and with lateral openings 32 and 32' which permit support of stem 20 in either direction horizontally as indicated in Fig. 3.

Longitudinally slidable on stem 20 are two

clutch members or climbing member 35, 35 capable also of a slight lateral movement, at right angles to the wearing-faces 20' of stem 20. Each member 35 carries a gripper block 60 36 seated somewhat loosely in a pocket 37 which preferably has a convex bottom, as shown at 38, and the gripper block is so formed that, when in engagement with face 20', downward movement of member 35 on 65 stem 20 is prevented.

Also slidably mounted on stem 20 is a load-engaging member 40 having rollers 41, 41, engaging stem 20, and a load-receiving 70 step 42.

Member 40 is provided, opposite the channel of stem 20, with two vertically-spaced eyes 43 and 44 into which are projected the upper and lower fingers 45 and 46 of a lever-carrier 47 seated in the channel of 75 stem 20 and having a middle finger 48 upon which the operating lever 49 is pivoted.

The hub of lever 49 carries a pinion 50, the teeth of which mesh with rack-teeth 51 carried by the clutch members 35. 80

Members 35 are connected by a plate or bar 52, the middle of which is engaged by the outer end of a spring 53 lying in a passage 54, formed through carrier 47 and acting, at its inner end through the rounded 85 end of a pin 55, upon the stem 20, the arrangement being such that spring 53 yieldingly holds the clutch blocks 36 against face 20' of stem 20.

Each carrier 35 is provided with a projection 57 which lies adjacent a segmental surface 58 on lever 49 and carrier 47 is permitted to rock on stem 20, as indicated in Fig. 8, for a purpose which will appear. 90

Member 40 is perforated at 60 and provided with an adjacent gripping surface 61 with which a gripping-cam 62 may operate.

In order that the device may be used as a vise, for gripping pipe and other articles, 100 the stem 20 may be supported as shown in Fig. 3, and I provide a swinging jaw 70 (Fig. 1) which may be substituted for finger 22.

Lever 49 is provided with a pocket 71 105 for the reception of the extension shown in Fig. 4, said extension having various nut-sockets 72 so that it may be used as a wrench.

In operation, oscillation of lever 49 will 110 cause members 35 to climb stem 20 and thus raise member 40. If, however, the lever

49 be laterally swung, alternately, in opposite directions at the ends of its oscillations (as shown in Fig. 8), the climbers 35 will be alternately shifted, against the action of 5 spring 53, so as to withdraw the clutch blocks 36 alternately from face 20', and, as these clutch blocks only serve to resist downward movement on the stem 20, when they are in actual engagement with face 20', 10 it is apparent that the alternate lateral reciprocation of lever 49 will permit the climbers 35 to be shifted downwardly on stem 20 during the period when they are laterally displaced, as indicated in Figs. 8 15 and 11.

The device is useful not only as a lifting jack but also as a wire stretcher and in many other ways which will naturally suggest themselves, and in the claims the term "lifting jack" is merely used as typical rather than limiting.

In order to obtain a continuous sliding return of the load-engaging member along stem 20, the lever 49 may be swung to a position substantially parallel with the stem. 25 The carrier 47 may then be tilted, finger 46 fulcruming upon an adjacent portion of the member 40, so that both of the clutch-carrying members 35, 35 will be simultaneously 30 shifted laterally to the position illustrated in the right hand side of Fig. 8; whereupon, the entire load-engaging member may be shifted longitudinally on stem 20 in either direction.

35 The tilting mentioned above is obtained by means of a cam surface 80 on lever 49, said cam surface 80 coming into engagement with the upper surface of eye 44 when the lever 49 is swung up parallel with stem 20.

40 Swing of lever 49 is limited in downward direction by engagement with eye 44, as shown in Fig. 1 and, in order to prevent cam 80 from coming into accidental engagement with eye 44, normal swing of lever 49 in the upper direction is prevented by a 45 projection 81 which, conveniently, is the pivot pin of the upper roller 41 and of sufficient length to be pushed lengthwise so as to occupy either a lever obstructing position or one out of the line of movement 50 of the lever.

I claim as my invention:

1. A lifting jack comprising a main stem, a load-engaging member slidably mounted 55 on the stem, a pair of climbing members mounted on the stem and movable longitudinally and laterally, a pivoted operating lever carried by the load-engaging member, interengaging means between said lever and climbing members for causing relative reciprocation of the climbing members upon oscillation of the lever, means for normally 60 causing the climbing members to actively interengage with the stem in one direction 65 of movement while permitting freedom of

movement in the opposite direction, and means permitting lateral movement of the lever to cause lateral shifting of the climbers to permit reverse movement of the climbers on the stem. 70

2. A lifting jack comprising a main stem, a load-receiving member slidably mounted on the stem, a pair of clutch members slidably mounted on the stem and having a clutch interengagement with the stem active 75 in one direction only, a shiftable carrier carried by the load-engaging member, an operating lever pivoted on said carrier, means carried by said operating lever for engaging the clutch members to reciprocate the same 80 upon oscillation of the lever, a spring nested in said carrier for normally holding the clutch members in active relationship with the stem, the lever being so formed that, by tilting its carrier it will engage the clutch member to shift it to inactive position pending and during oscillation of the lever, for the purpose set forth. 85

3. A lifting jack comprising a main stem, a load-receiving member slidably mounted 90 on the stem, a pair of clutch members slidably mounted on the stem and having a clutch interengagement with the stem active in one direction only, a shiftable carrier carried by the load-engaging member, an operating lever pivoted on said carrier, means carried by said operating lever for engaging the clutch members to reciprocate the same upon oscillation of the lever, a spring 95 for normally holding the clutch members in active relationship with the stem, the lever being so formed that, by tilting its carrier it will engage the clutch members to shift them to inactive positions pending and during oscillation of the lever, for the purpose 100 set forth. 105

4. A lifting jack comprising a main stem, a load-receiving member slidably mounted on the stem, a pair of clutch members slidably mounted on the stem and having a 110 clutch interengagement with the stem active in one direction only, a shiftable carrier carried by the load-engaging member, an operating lever pivoted on said carrier, means carried by said operating lever for engaging the clutch members to reciprocate the same upon oscillation of the lever, the lever being so formed that, by tilting its carrier it will engage the clutch members to shift them to inactive positions pending and during oscillation of the lever, for the purpose 115 set forth. 120

5. A lifting jack comprising a main stem, a load-engaging member slidably mounted on said stem, a pair of climbing members 125 slidably mounted on the stem and provided with clutch portions active upon the stem in one direction, rack-teeth carried by said climbing members, a lever carrier rockably mounted in the load-engaging member, an 130

operating lever pivoted on said rocking carrier and provided with a pinion engaging the racks of the climbers, and also provided with a portion adapted to engage and laterally displace the climbers upon lateral displacement of the lever and during oscillation thereof, a plate connecting said climbers, a spring nested in the rocking carrier engaging said plate to normally urge the clutch members to active position.

6. A lifting jack comprising a main stem, a load-engaging member slidably mounted on said stem, a pair of climbing members slidably mounted on the stem and provided with clutch portions active upon the stem in one direction, rack-teeth carried by said climbing members, a lever carrier rockably mounted in the load-engaging member, an operating lever pivoted on said rocking carrier and provided with a pinion engaging the racks of the climbers, and also provided with a portion adapted to engage and laterally displace the climbers upon lateral displacement of the lever and during oscillation thereof.

7. A lifting jack comprising a main stem, a load-engaging member slidably mounted on said stem, a pair of climbing members slidably mounted on the stem and provided with clutch portions active upon the stem in one direction, rack-teeth carried by said climbing members, a lever carrier rockably mounted in the load-engaging member, an operating lever pivoted on said rocking carrier and provided with a pinion engaging the racks of the climbers, and also provided with a portion adapted to engage and laterally displace the climbers upon lateral displacement of the lever and during oscillation thereof.

7. A lifting jack comprising a main stem, a load-engaging member slidably mounted on said stem, a pair of climbing members slidably mounted on the stem and provided with clutch portions active upon the stem in one direction, rack-teeth carried by said climbing members, a lever carrier rockably mounted in the load-engaging member, an operating lever pivoted on said rocking carrier and provided with a pinion engaging the racks of the climbers, and also provided with a portion adapted to engage and laterally displace the climbers upon lateral displacement of the lever and during oscillation thereof.

In witness whereof, I have hereunto set my hand at Indianapolis, Indiana, this 28th day of March, A. D. one thousand nine hundred and twenty-two.

GEORGE WARREN WILLIAMSON.
